UNITED STATES PATENT OFFICE.

DE VER H. WARNER, OF BRIDGEPORT, CONNECTICUT.

DESIGN FOR A GARMENT-FASTENER.

SPECIFICATION forming part of Design No. 28,645, dated September 18, 1894.

Application filed February 2, 1894. Serial No. 498,925. Term of patent 3½ years.

To all whom it may concern:

Be it known that I, DE VER H. WARNER, a citizen of the United States, residing at Bridgeport, in the county of Fairfield and State of Connecticut, have invented a new Design for Fasteners or Holders of Garment-Supporters, of which the following is a specification.

My invention relates to a new and original design for holders or fasteners for garment supporters, of which the following is a specification, reference being had to the accompanying drawings, in which—

Figure 1 is a perspective view of my design for a fastener or holder. Fig. 2 is a plan view thereof, and Fig. 3 is a sectional view thereof on the line $x-x$ of Fig. 2.

In the drawings, A, represents a fastener plate, provided with an opening 1, and a slot 2, of less diameter than the opening 1, the slot merging into the opening. At each side of the slot are projections 3.

The essential feature of my design consists in the projections on opposite sides of the slot.

What I claim is—

The design for a fastener substantially as shown and described.

In testimony whereof I have signed my name to this specification in the presence of two subscribing witnesses.

DE VER H. WARNER.
